Claims priority, application Netherlands
December 12, 1953.

10: Claims. (Cl. 315—21)

This invention relates to devices for reproducing color television images and to a cathode-ray tube for use in such devices.

Various systems and devices have been proposed for reproducing color television images including semi-electronic, semi-mechanical and fully electronic devices. The latter usually comprise a cathode ray tube with a luminescent screen constituted of regularly-arranged discrete surface areas covered with luminescent materials radiating differently-colored light under electron bombardment. A cathode-ray tube used in such systems contains one or more color-selection electrodes capable of directing the electron beam to a given surface area radiating the desired color, the color image being built up by changing the potential applied to said color-selection electrodes. Many different forms of color-selection electrodes have been proposed. The present invention relates only to devices in which color-selection is effected by means of two grids, hereinafter termed color-selection grids, the active surfaces of which are constituted only by parallel wires. That is to say, the wires of each grid extend parallel to each other as well as parallel to the wires of the other grid. These grids operate in such manner as to produce a focal line on the viewing screen whose location is determined by the potential of the color-selection grids. A satisfactory focal line and sufficient intensity of the light radiated by the screen require a field accelerating the electrons after passing through the color-selection grids. This field is produced by means of a so-called field electrode which, viewed from the cathode, is disposed behind the color-selection grids. The field electrode may, for example, consist of a grid, an electron-transmitting conductive, e. g. metal, layer provided on the screen, conductive material mixed with the luminescent material or a self-conductive luminescent material on the screen. In the last-mentioned three cases, which are to be preferred over a separate field electrode, the latter is consequently united with the screen to form an assembly. A construction of this type will be described later by way of example.

As is customary, to the screen is applied a high D. C. potential, usually the highest potential in the cathode-ray tube. In order to obtain a focusing effect between the color-selection grids and the screen, the ratio between the mean or D. C. potential of the color-selection grids and the potential of the screen is required to be 1:4, since under these circumstances the focal point of the electron beam just lies on the screen. A high-luminosity image requires a very high voltage, generally from 10 to 25 kv., to be applied to the screen, and therefore, the D. C. potential of the color-selection grids must be several kv. Satisfactory control with such color-selection grids is only possible if the control voltages to be supplied thereto are also high. Thus, color-selection voltages of, say, 300 to 500 v. are used, which is very objectionable. Further, the two color-selection grids have considerable surface areas and, hence, a considerable capacitance relative to each other, so that the charge

2

to be supplied per unit time, which is determined, as is known, by the product of angular frequency, capacitance and potential, is very considerable in systems with a high color-selection frequency. This, of course, imposes very high requirements on supply conductors, current lead-through arrangements and equipment producing the color-selection control voltages. The present invention has as its chief object to provide a device wherein low color-selection voltages are sufficient.

- 10 A device in accordance with the invention for reproducing color television images comprises a cathode-ray tube, and means for horizontal and vertical scanning of the electron beam, which means generate a deflection field in the cathode-ray tube. The former comprises an electron gun, a viewing screen emitting light under electron bombardment, two color-selection grids which are disposed between the screen and the electron gun and having active surfaces which consist exclusively of parallel wires, and a field electrode disposed on the side of 15 the color-selection grids remote from the cathode. The device is further characterized by the fact that the mean or D. C. potential of the color-selection grids does not exceed one-tenth of the potential of the field electrode. Still further, a fine-meshed grid is provided between the 20 color-selection grids and the field electrode having meshes of a width at most equal to one-tenth of the spacing between two successive wires of a color-selection grid and a potential at most equal to the mean or D. C. potential of the color-selection grids and not more than 10 volts 25 lower than the lowest potential of a color-selection grid. Finally, a focussing electrode at a potential higher than the mean potential of the color-selection grids and lower than the potential of the field electrode is disposed between the deflection field and the color-selection grids. 30
- 35 The means for line- and image-deflection, i. e., horizontal and vertical scanning, of the electron beam may, as is known, operate either electro-magnetically or electro-statically. In either case, a deflection field is produced at a particular area within the cathode-ray tube. 40 This deflection field acts upon the electron beam produced by the electron gun. In this context, the term "electron gun" is to be understood to mean the electrode aggregate producing a concentrated electron beam.

The viewing screen may comprise discrete, evenly-divided surface areas of luminescent materials luminescing in different colors upon excitation by the electron beam. Alternatively, however, the screen may radiate only mono-colored light throughout its surface and this light may fall on a filter comprising evenly-arranged discrete surface areas of different spectral transparency or reflection power. In this case, the screen may also be coated with luminescent material or for example, be a so-called incandescent screen; that is to say, a surface heated by the energy resulting from impinging electrons 55 to such a degree as to radiate light.

Since the color-selection grids consist exclusively of parallel wires, luminous strips extending parallel to the direction of the grid wires are produced on the screen. By applying control voltages to the color-selection grids, the location of these luminous strips is shifted in a direction at right angles to the direction of the grid wires. The various luminescent materials or the surface areas of the filter extend in the form of strips parallel to the wires of the color-selection grids.

65 As has been stated above, the location of the luminous lines on the screen is determined by the potentials of the color-selection grids. To this end, suitable control voltages, generally in the form of stepped waves, are applied to the grids, preferably in phase-opposition, in order to secure a symmetrical effect. Naturally, the geometrical positioning of the two color-selection grids is also important for obtaining a satisfactory effect. As

is known, it is most simple to arrange the two grids in one plane so that the wires of one grid alternate with the wires of the other grid. For the sake of convenience, the invention will be explained, by way of example, with reference to such a configuration of the color-selection grids, without, however, the invention being limited thereto. In fact, the two grids may alternatively extend in two different planes.

Since, in accordance with the invention, the mean potential of the color-selection grids is not made higher than one-tenth of the potential of the screen, i. e., field electrode, low color-selection voltages will suffice. However, unless special steps are taken, this low potential will prevent adequate focusing of the electron beam between the color-selection grids and the screen, since in this case the potential ratio between the color-selection grids and the screen is much larger than 1:4.

In order to re-establish the focusing, a fine-meshed grid might be provided between the color-selection grids and the screen, the grid having a potential substantially corresponding to three times the mean potential of the color-selection grids. If the meshes of this grid are sufficiently small no appreciable concentration occurs thereat. Due to the potential ratio of 3:1, the electron beam is substantially concentrated on the fine-meshed grid, and eventual concentration occurring between the fine-meshed grid and the viewing screen finally results in that focal lines just fall on the screen. However, this method has a serious limitation, because a large number of secondary electrons is unavoidably dislodged at the color-selection grids and at the fine-meshed grid. All these electrons are accelerated in the direction of the screen where they give rise to annoying light radiations. Hence, this solution for re-establishing the focusing is objectionable and therefore the invention does not bear relationship thereto.

Another disadvantage accompanying the low potential of the color-selection grids is that the electrons have a low velocity in a large part of the tube. In order to mitigate this disadvantage, a retarding field is produced between the deflection field and the color-selection grids. Consequently, the electrons retain their high velocity from the deflection field to the retarding field, and, notwithstanding this, they are sufficiently retarded upon reaching the color-selection grids as to readily be controlled by the slight potential variations at said grids. The retarding field may at the same time provide for the focusing by disposing, between the color-selection grids and the screen, a fine-meshed grid whose potential is at the most equal to the mean potential of the color-selection grids and is not more than 10 volts lower than the lowest potential of a color-selection grid. In other words, the upper potential limit of this grid is the color-selection grid D. C. potential, and the lower potential limit is 10 volts below the lowest potential attained by a color-selection grid when the color-switching or selecting signals are applied thereto. It is advantageous to make the potential of this fine-meshed grid slightly lower than the potential of the color-selection grids in order to prevent any secondary electrons produced at the color-selection grids from reaching the screen.

Extensive investigations have shown that the mesh-width, that is to say, the spacing between the center lines of two adjacent wires of the fine-meshed grid, should at most be equal to one-tenth of the spacing between two successive wires of a color-selection grid. Preferably, a normally wound grid is used for the fine-mesh grid, which, consequently, comprises two sets of wires extending in directions at right angles to each other. If desired, it is sufficient to use wires extending parallel to the wires of the color-selection grids, but since the grid has very fine meshes this usually entails serious structural difficulties. Since the fine-meshed grid unavoidably collects electrons, a grid having a very small shadow ratio is preferably used. - The spacing between the fine-

meshed grid and the nearest color-selection grid, together with the mean potential of the color-selection grids, determines the required strength of the aforesaid retarding field. In the case of a high field strength, the spacing is required to be small but not smaller than is permissible in connection with the capacitance between the fine-meshed grid and the color-selection grids.

The retarding field between the deflection field and the color-selection grids is produced by an electrode which is disposed between the color-selection grids and the deflection field and has a potential higher than the mean potential of the color-selection grids but lower than the potential of the field electrode. This electrode, which is termed the focusing electrode, may for example, be a second fine-meshed grid. Alternatively, however, an annular electrode may be used which surrounds a part of the space before the color-selection grids. If desired, these two constructions may be combined.

A further improvement is obtained by dividing the annular focusing electrode into two insulated parts and applying a voltage between these two parts. In this case, the annular electrode, which is situated at the cathode side, requires a potential exceeding that of the first annular electrode, but at the most equal to the potential of the screen. For the fine-meshed grid, which may be situated at the cathode side of the color-selection grids, it also holds that the width of the meshes should at the most be equal to one-tenth of the spacing between two successive wires of a color-selection grid and that it should have a small shadow ratio. Naturally, the several electrodes strongly influence the field within the cathode-ray tube in the proximity of the color-selection grids. Several steps may be resorted to in order to improve the form of said field. This will be explained with reference to the accompanying drawing in which

Fig. 1 shows diagrammatically those parts of a device according to the invention for reproducing color images;

Figs. 2 to 7 are detail views of modifications showing different arrangements of the aggregate of color-selection grids, viewing screen, fine-meshed grid and the focusing electrode.

Referring now to Fig. 1, the cathode-ray tube comprises an envelope including a neck 1 and a conical portion 2 secured thereto. The neck 1 contains a beam-producing electron gun 3. Before entering the conical portion 2, the electron beam is deflected by deflection coil systems 4 and 5 producing a deflection field within the tube. The conical portion 2 of the tube contains a luminescent screen 7 and color-selection grids 8, 9 placed in front thereof and comprising parallel wires extending at right angles to the plane of the drawing. By applying suitable control voltages to the grids 8 and 9, preferably in phase-opposition as described for example in a copending U. S. application Serial No. 298,942, filed July 15, 1952, the electron beam is directed to a given point of the luminescent screen 7.

The screen 7 is united with the field electrode which consists of an electron-transmitting, conductive, for example, metal, layer 6 provided at the cathode side of the screen. The luminescent material, for example, luminescing red, blue and green, extends in the form of strips parallel to the wires of the grids 8 and 9. As is customary in such systems, the said strips alternate in regular succession.

To the viewing screen is applied a high voltage, e. g. about 15,000 volts, relative to the cathode, the color-selection grids 8 and 9 being connected to such a point of the source of potential that the mean or D. C. potential thereof does not exceed one-tenth of the potential of the viewing screen 7. A suitable value is, for example, about 150 volts.

In front of the color-selection grids 8 and 9 is provided a ring-shaped electrode 11 surrounding a part of the space between the deflection field and the grids. Disposed behind the color-selection grids is a fine-meshed

grid 10, the meshes of which have a width at the most equal to one-tenth of the spacing between two successive wires of the grid 8 or the grid 9, that is to say one-tenth of the spacing a . Typical spacing for the grids 8, 9 is about 0.5 mm., and for the mesh 10 about 0.06 mm. The fine-meshed grid 10 is connected to a point of the source of potential so as to acquire a potential at the most equal to the mean or D. C. potential of the color-selection grids and equal to or above a potential 10 volts below the lowest potential of either of said grids. A suitable value is about 120 volts.

The interacting electrodes 11, 8, 9 and 10 produce such a field that each electron beam forms a focal line on the viewing screen 7. As a matter of fact, a retarding lens largely responsible for the focusing is produced between the electrode 11 and the grids 8, 9. Since this lens has a retarding action, the electrons reach the grids 8, 9 at a low velocity so that they can be readily controlled by small voltage variations therein.

As will be appreciated, an annular electrode 11 as shown in Fig. 1 right in front of the grids 8 and 9, particularly if they have large surfaces, will not yield a uniform field. Therefore, in one embodiment of the invention as shown in Fig. 2, the annular electrode 11 at the side of the color-selection grids is closed by means of a fine-meshed grid 12. In this figure, the remaining electrodes bear the same reference numerals as in Fig. 1. In order to reduce the lens effect of the meshes of the grid 12 so as to avoid any appreciable widening of the focal line on the screen 7, the meshes of the grid 12 should at the most have a width equal to one-tenth of the spacing between two successive wires of a color-selection grid, the same as the grid 10.

When the electron beam is deflected by the line- and picture-deflection means 4 and 5, the beam, at the edges of the color-selection grids, is obliquely incident on the plane of these grids, which results in distortion and blurred edges. In a device according to the invention, these errors are avoided by disposing, between the retarding lens in front of the color-selection grids and these grids, a ring-shaped electrode which adjoins the edges of the surfaces of the color-selection grids but is not electrically connected thereto. To this electrode, a voltage is applied such that its potential corresponds to the mean potential of the color-selection grids. A construction of this type is shown in Fig. 3, in which the electrodes corresponding to those shown in Figs. 1 and 2 are provided with the same reference numerals. A ring-shaped electrode 13 is disposed between the ring-shaped focusing electrode 11 and the color-selection grids 8, 9, the lens formed between the electrodes 11 and 13 deflecting an obliquely-incident beam 14 in such manner as to strike the plane of the grids 8 and 9 substantially at right angles.

A further improvement upon the construction shown in Fig. 3 is obtained by means of the construction depicted in Fig. 4 in which the electrode 11 is covered, on the side remote from the cathode, with a fine-meshed grid corresponding to the grid 12 in Fig. 2. This construction has the advantage over the construction shown in Fig. 3 that the lens formed between the electrodes 11 and 13 has no parts with negative lens-effect wherein divergence occurs, contrary to the construction shown in Fig. 3, because the field has the form shown in broken lines. In the construction shown in Fig. 4, the field is also indicated in broken lines and it is found that by introduction of the grid, only one half of the lens of the construction shown in Fig. 3 remains, and this half has the desired directional effect on the electron beam.

Fig. 5 shows another construction in which the electron beam is retarded in two steps. In front of the electrode 11 is provided an annular electrode 15 whereof the potential exceeds that of the ring-shaped focusing electrode 11 and at the most corresponds to the potential of the screen 7. This construction enables greater freedom in choos-

ing the field strength at the cathode side of the color-selection grids. As a matter of fact, this choice determines the focusing of the electron beam, the electrode aggregate moreover fulfilling the function of bending the deflected beam again parallel to the axis.

The ring-shaped electrode 11 used in the constructions shown in Figures 1 to 5 may be replaced by a simple, fine-meshed grid disposed in front of the color-selection grids. This construction is shown in Fig. 6. In this case, the fine-meshed grid 16 has applied to it a potential exceeding the mean potential of the color-selection grids 8, 9 and lower than the potential of the screen 7. This construction has the advantage that the field strength at the cathode side of the color-selection grids is equal throughout the grids, which is of importance for satisfactory focusing throughout the image. In this construction, the electron beam will be deflected particularly at the edges of the grid 16 from the center of the grid onwards. This is just the reverse of what is preferably desired, that is to say, the electron beam should reach the color-selection grids at right angles even after deflection. In this case it is therefore advantageous to dispose a ring-shaped electrode in front of the grid 16, which electrode is connected to a point of a source of potential such that its potential is lower than that of the grid 16. This construction is shown in Fig. 7 in which corresponding electrodes are provided with the same reference numerals. A ring-shaped electrode 17 having a potential lower than that of the grid 16 is disposed in front of the fine-meshed grid 16 whereof the meshes have a width smaller than one-tenth of the spacing between two successive wires of a color-selection grid. Between the electrode 17 and the wire gauze 16, there is produced a positive accelerating lens bending the deflected beam parallel to the axis.

In order to illustrate a few specific embodiments of the invention, the electrodes of Fig. 1 are spaced as follows from one another:

	Mms.
Grid 10—screen 6	8
Grid 10—grids 8 and 9	2
Grids 8 and 9—electrode 11	15

Further, the spacing a between the wires of the grid 8 is 1 mm. The width of the meshes of the grid 10 is 0.06 mm. The potentials applied to the various electrodes are:

	Volts
Screen 6	15,000
Grid 10	120
Grids 8, 9	150
Electrode 11	5,000

In the embodiment illustrated in Fig. 6 the values for the electrodes 6, 8, 9 and 10 are the same as for the corresponding electrodes in the embodiment illustrated in Fig. 1. The width of the meshes of grid 16 is 0.06 mm., the distance between grid 16 and the plane of the grids 8 and 9 is 30 mms. and the potential of grid 16 is 5000 volts.

While we have described our invention in connection with specific embodiments and applications, other modifications thereof will be readily apparent to those skilled in this art without departing from the spirit and scope of the invention as defined in the appended claims.

What is claimed is:

1. A device for reproducing color-television images comprising a cathode-ray tube including an electron gun producing an electron beam and means producing a deflection field within the cathode-ray tube for vertically and horizontally deflecting the beam, said tube further including a viewing screen radiating light under electron-bombardment, two color-selection grids disposed between the screen and the electron gun and the active surfaces of which consist of parallel wires, and a field electrode disposed on that side of the color-selection grids remote

from the gun; means applying a given potential to the field electrode; means applying potentials to the color-selection grids at which the mean potential of the color-selection grids does not exceed one-tenth of the potential of the field electrode; said tube also including a fine-mesh grid disposed between the color-selection grids and the field electrode and having meshes of a width equal to at most one-tenth of the spacing between two successive wires of a color-selection grid; means applying to said fine-mesh grid a potential at most equal to the mean potential of the color-selection grids and not more than ten volts below the lowest potential of a color-selection grid; said tube also including a focusing electrode disposed between the deflection field and the color-selection grids; and means applying to said focusing electrode a potential higher than the mean potential of said color-selection grids and lower than the potential of the field electrode.

2. A device as claimed in claim 1 in which the focusing electrode comprises an annular electrode surrounding the space before the color-selection grids.

3. A device as claimed in claim 2 in which a second annular electrode having a potential substantially corresponding to the mean potential of the color-selection grids is disposed between the annular electrode and the color-selection grids.

4. A device as claimed in claim 2 in which a second annular electrode having a potential higher than that of the first annular electrode and at the most equal to the potential of the field electrode is disposed between the deflection field and the annular electrode.

5. A device as claimed in claim 1 in which the focusing electrode is a grid the meshes of which have a width at the most equal to one-tenth of the spacing between two successive wires of a color-selection grid.

6. A device for reproducing color-television images comprising a cathode-ray tube including an electron gun producing an electron beam and means producing a deflection field within the cathode-ray tube for deflecting the beam, said tube further including a viewing screen radiating light under electron-bombardment, two color-selection grids disposed between the screen and the electron gun and the active surfaces of which consist of parallel wires, and a field electrode disposed on that side of the color-selection grids remote from the gun; means applying a given potential to the field electrode; means applying potentials to the color-selection grids at which the mean potential of the color-selection grids does not exceed one-tenth of the potential of the field electrode; said tube including a first fine-mesh grid disposed between the color-selection grids and the field electrode and having meshes of a width equal to at most one-tenth of the spacing between two successive wires of a color-selection grid; means applying to said fine-mesh grid a potential at most equal to the mean potential of the color-selection grids and not more than ten volts below the lowest potential of a color-selection grid; said tube including an annular focusing electrode surrounding the space before the color-selection grids; means applying to said focusing electrode a potential higher than the mean potential of said color-selection grids and lower than the potential of the field electrode; and said tube also including a second fine-mesh grid closing off the end of the annular electrode adjacent the color-selection grids, said second grid having meshes of a width at the most equal to one-tenth of the spacing between two successive wires of a color-selection grid.

7. A device for reproducing color-television images comprising a cathode-ray tube including an electron gun producing an electron beam and means producing a deflection field within the cathode-ray tube for deflecting the beam, said tube further including a viewing screen radiating light under electron bombardment, two color-selection grids disposed between the screen and the electron gun and the active surfaces of which consist of

parallel wires, and a field electrode disposed on that side of the color-selection grids remote from the gun; means applying a given potential to the field electrode; means applying potentials to the color-selection grids at which the mean potential of the color-selection grids does not exceed one-tenth of the potential of the field electrode, said tube including a first fine-mesh grid disposed between the color-selection grids and the field electrode and having meshes of a width equal to at most one-tenth of the spacing between two successive wires of a color-selection grid; means applying to said fine-mesh grid a potential at most equal to the mean potential of the color-selection grids and not more than ten volts below the lowest potential of a color-selection grid; said tube also including a second fine-mesh grid disposed between the deflection field and the color-selection grids and having meshes of a width equal to at most one-tenth of the spacing between two successive wires of a color-selection grid, and an annular electrode surrounding the space before the second grid; means applying to said second grid a potential higher than the mean potential of said color-selection grids and lower than the potential of the field electrode; and means applying to said annular electrode a potential lower than that applied to said second grid.

8. A device for reproducing color-television images comprising a cathode-ray tube including an electron gun producing an electron beam, a luminescing screen radiating light under electron-bombardment and constituted of a plurality of parallel strips each arranged to produce light in one of a plurality of predetermined colors, and means producing a deflection field within the cathode-ray tube for causing said beam to scan said screen; said tube further including a pair of color-selection grids disposed between the screen and the electron gun and the active surfaces of which comprise parallel wires for causing said beam to selectively impact certain of said strips of said screen, and a field electrode disposed on that side of the color-selection grids remote from the gun; means applying a given potential to the field electrode and means applying potentials to the color-selection grids at which the mean potential of the color-selection grids is less than one-tenth of the potential of the field electrode; and means for retarding said beam and focussing said beam onto said screen including a fine-mesh grid disposed between the color-selection grids and the field electrode and having meshes of a width less than one-tenth of the spacing between two successive wires of a color-selection grid and another electrode disposed between the deflection field and the color-selection grids for establishing a retarding field for the beam before the grids; and means applying to said fine-mesh grid a potential less than the mean potential of the color-selection grids and not more than ten volts below the lowest potential of a color-selection grid and to said other electrode a potential above the mean potential of said color-selection grids and less than the potential of the field electrode, whereby application of color signals of low voltage and power to the color-selection grids is sufficient to produce a satisfactory color image.

9. A device as set forth in claim 8, wherein the color-selection grids lie in a common plane and said other electrode is an annular electrode surrounding the space before the color-selection grids.

10. A device as set forth in claim 8, wherein the color-selection grids lie in a common plane and said other electrode is a fine-mesh grid having meshes of a width less than one-tenth of the spacing between two successive wires of a color-selection grid.
